UNITED STATES PATENT OFFICE.

HERBERT FREEMAN FREDERIC, OF BATH, MAINE.

CORKING-MACHINE.

SPECIFICATION forming part of Letters Patent No. 777,502, dated December 13, 1904.

Application filed May 31, 1904. Serial No. 210,379. (No model.)

To all whom it may concern:

Be it known that I, HERBERT FREEMAN FREDERIC, a citizen of the United States, residing at Bath, in the county of Sagadahoc and 5 State of Maine, have invented new and useful Improvements in Corking-Machines, of which the following is a specification.

This invention relates to machines for corking bottles; and its object is to provide a simple and effective apparatus for doing this work whereby the frequent breakage of bottles which results when a hand-operated hammer is used to drive the corks is entirely avoided.

The invention consists in a table to support 15 the bottle, jar, or the like, a vertically-adjustable standard, an arm hinged to the top of said standard, a hammer pivoted to the end of said arm, a treadle to depress said arm, a spring to lift it, and a parallel-ruler device for 20 preserving the upright position of the hammer during its movements.

In the accompanying drawings, Figure 1 is a side elevation of my improved machine. Fig. 2 is a front view of the upper portion of 25 the same. Fig. 3 is a top plan view. Fig. 4 shows the adjustable gage. Fig. 5 is a sectional elevation, on a larger scale, of the upper end of the standard. Fig. 6 is a rear view of the spring on a larger scale. Fig. 7 is a 30 plan view of the plate at the lower end of the pull-rod.

The several parts of the apparatus are mounted on a firm rigid support, such as a shelf 1, on which is secured the collar 2, 35 through which passes the upright standard 3, which is vertically adjustable in the collar by means of a set-screw 4. The standard is preferably composed of a piece of metal tubing, and a head 5 is secured to its upper end, preferably by means of a screw-threaded shank 6 engaging with internal threads in the tubing. Pivoted to the head 5 is an arm, preferably composed of two parallel curved bars 7, whose outer ends are pivotally attached to a hammer 8. An upright pull-rod 9 passes through 45 a hole in the shelf 1 and is pivoted to the arm between the head 5 and the hammer 8, preferably passing between the bars 7 at the point 10. The rod extends above the bars parallel 50 with the shank 11 of the hammer. The up-

per end of the rod is connected with the upper end of said shank by means of a link 12, which is pivoted to both. This arrangement constitutes a parallel-ruler construction, so that the shank of the hammer will always remain 55 parallel with the rod 9 irrespective of the vertical vibrations of the arm 7.

The bottom of the pull-rod is provided with a plate 13, in which is a slot 14 to permit the attachment thereto of a strap 15, which is also attached to a treadle 16. On the treadle is a toe 17, adapted to come in contact with the block 18, in which the treadle is hinged, and thus limit the upward movement of the treadle and the hammer. Secured to the lower end 60 of the standard 3 is a spring 19, preferably composed of two parallel coils of wire provided with tongues 20, which enter the tubular standard and are there secured by a set-screw 21. The springs also have arms 22, 65 which engage with holes 23 in the plate 13, and thus exert an upward thrust on the pull-rod to normally keep it raised, said springs, in connection with bars 7, constituting a parallel-rule connection. 75

On the side of the collar 2 is a clamp 24, through which passes a wire 25, having at its forward end a curved transverse portion 26. This wire serves as a gage to locate the bottle 27 accurately under the hammer. By means 80 of the clamp the gage can be set in or out to suit various sizes of bottles.

The operation of the machine is as follows: The workman inserts a cork 28 in the bottle 27, places the bottle against the gage 26 under 85 the hammer 8, and presses the treadle 16 downward with his foot. This swings down the arm 7 and the hammer 8, the latter exerting a firm steady pressure on the stopper and forcing it into the bottle. The pivotal 90 connection of the rod with the arm and also with the shank of the hammer through the link 12 compels the face of the hammer to remain always parallel with the top of the bottle, and thus the stopper cannot be canted 95 over during the descent of the hammer. When the stopper has been forced home, the operator relieves the pressure on the treadle, and the spring 19 lifts the rod, hammer, and treadle to their original positions. 100

If a taller or a shorter bottle is to be corked, the hammer can be accommodated thereto by adjusting the standard up or down in the collar 2 and lengthening or shortening the strap 5 15 accordingly.

The means I have shown and described for producing the parallel-ruler movement of the hammer are the ones I prefer to use; but it is evident that other equivalent means may be 10 substituted therefor without departing from the spirit of my invention.

Having thus described my invention, what I claim is—

1. In a machine for corking bottles, the combination with a suitable support, of a standard, an arm hinged thereto, a hammer pivoted to said arm, means for vibrating said arm, a parallel-ruler device for preserving the upright position of the hammer, means for supporting 20 the hinged arm.

2. In a machine for corking bottles, the combination with a suitable support, of a standard, an arm hinged thereto, a hammer pivoted to said arm, a pull-rod also pivotally attached to 25 said arm, means for supporting the arm and a link connecting the pull-rod and the hammer.

3. In a machine for corking bottles, the combination with a suitable support, of a standard, an arm hinged thereto, a hammer pivoted to 30 said arm and having an upwardly-extending shank, a pull-rod pivotally attached to said arm and extending above the same, means for supporting the arm, and a link connecting the upper ends of said rod and shank.

35 4. In a machine for corking bottles, the combination with a suitable support, of a collar thereon, a standard adjustable in said collar, a hammer pivotally supported from the upper end of said standard, a rod for actuating 40 said hammer, a treadle for moving said rod, means for supporting the hammer, and adjustable connections between said rod and treadle.

5. In a machine for corking bottles, the combination with a suitable support, of a standard passing down through the same, an arm hinged 45 to said standard, a hammer carried by said arm, a pull-rod for actuating said hammer, said rod passing down through said support, a supporting-spring attached to the standard and engaging with said rod, and a treadle for 50 moving said rod.

6. In a machine for corking bottles, the combination with a suitable support, of a standard passing down through the same, a hammer pivotally supported on said standard, a pull-rod 55 for actuating said hammer, a plate on the lower free end of said pull-rod, a spring composed of two coils of wire attached at one end to the standard and having their other ends engaging with said plate, and supporting and actuating the pull-rod, and a treadle connected with said plate.

7. A machine for corking bottles, comprising the collar 2, having the set-screw 4 and clamp 24, the gage 25, the tubular standard 3 passing through said collar, the head 5 screwed into the upper end of said standard, the arm composed of the two parallel bars 7 hinged to the head 5, the hammer 8 pivoted to the arm and having an upright shank 11, the pull-rod 9 pivoted to the arm, the link 12 pivoted to the rod and to the shank, the plate 13 on the rod 9, the supporting-spring 19 secured to the lower end of the standard and engaging with 60 said plate, the treadle 16 having the toe 17, 70 and the strap 15 connecting the treadle with the plate 13.

In testimony whereof I have signed my name to this specification in the presence of two subscribing witnesses.

HERBERT FREEMAN FREDERIC.
